Application March 19, 1942, Serial No. 435,382

16 Claims.

(Cl. 200—82)

This invention relates to circuit breakers and has for an object the provision of a circuit breaker operating mechanism having an improved shock-absorbing system for stopping the moving parts with minimum shock.

In connection with circuit breakers embodying high speed operating mechanisms, it is important to provide a reliable means for stopping the moving parts without excessive shock in order to avoid damage to the circuit breaker and its mechanism. This is particularly important in gas blast compressed gas operated circuit breakers due to the nature of the mechanism, and the supporting insulators which are usually composed of porcelain. If the compressed air or gas operating means is to be of simple construction, it is not practical to utilize air dashpots for absorbing shock. Moreover, air dashpots require frequent attention and are subject to failure.

An object of the invention is the provision of a high speed circuit breaker mechanism embodying an improved mechanical shock-absorbing system comprising several resiliently mounted masses which absorb the energy of the moving system without developing high impact forces.

Another object of the invention is the provision of a compressed gas operated circuit breaker embodying a shock-absorbing system including resilient bumper means built into the contact operating piston for absorbing energy at both ends of its travel.

Another object of the invention is the provision of a compressed air circuit breaker having an improved shock-absorbing system including an inertia bumper for absorbing some of the kinetic energy of the moving parts, the remaining energy being absorbed by a series of resilient means.

Another object of the invention is the provision of an improved shock-absorbing means for a circuit breaker, the shock-absorbing means including a resilient member which is deformed by impact and exerts a braking action as the decelerating motion continues.

The scope of the invention is defined in the appended claims. The invention itself, however, both as to structure and mode of operation together with additional objects and advantages thereof will be best understood from the following detailed description of one embodiment thereof when read in conjunction with the accompanying drawings, in which:

Figure 1 is a side elevational view of a com-

pressed air circuit breaker embodying the features of the invention;

Fig. 2 is an enlarged view, partly in section, of the contact operating mechanism and the shock-absorbing means; and

Fig. 3 is a fragmentary view, partly in section, showing the control valves of the mechanism.

The features of the present invention are illustrated as applied to a circuit interrupter mechanism similar to that disclosed in the copending application of L. R. Ludwig et al., Serial No. 431,394, filed February 18, 1942, and assigned to the assignee of the present invention.

15 Referring to Fig. 1 of the drawings, the reference numeral 11 designates a structural frame on which is mounted a plurality of hollow insulators 13, 15 and 17 of vitreous insulating material, only the first two of which are visible in Fig. 1. The insulator 17 is shown in Fig. 3. Secured to the upper end of the insulators 13, 15, and 17 is a casing 19 for housing the operating mechanism more fully shown in Fig. 2. The casing 19 supports a hollow insulator 21 of vitreous insulating material which, in turn, supports a circuit interrupting element 23. Another hollow insulator 25 extends upwardly from the element 23 and has a metallic terminal cap 27 secured on its upper end.

30 A stationary contact member 29 extends downwardly from the terminal cap 27 into the circuit interrupting element 23 and has a stationary contact 30 of the spring pressed, tulip or multiple finger type on the lower end thereof. A 35 vertically movable contact member 31 coacts with the stationary contact means 30 and extends downwardly through the element 23 and hollow insulator 21 into the casing 19. The lower end of the contact member 31 is coupled to

40 a compressed air operated piston of the operating mechanism as shown in Fig. 2, and which will be more fully described hereinafter. The movable contact member 31 is electrically connected to a terminal 33 by means of resilient 45 connector contact means 35 slidably engageable by the contact member 31, and by a connector strip 37 of conducting material.

Extinction of arcs drawn by the movable contact member 31 is accomplished by an arc extinguisher of the fluid or air blast type which may be of the form fully disclosed in the copending application of L. R. Ludwig and B. P. Baker, Serial No. 373,856, filed January 9, 1941, and assigned to the assignee of the present invention. Since the present application is not concerned

with the arc extinguishing structure, it is believed that the general designation of the arc extinguishing unit 60 which is adapted to be supplied with a blast of arc extinguishing fluid, such as compressed air, will be sufficient to the purpose at hand.

Fluid, under pressure, in this instance, compressed air for extinguishing the arc and also for the operating means of the interrupter, is stored in a tank 39 mounted within the frame 11. Compressed air is stored in the tank 39 and automatically maintained at a predetermined pressure by means of a suitable motor driven compressor unit, not shown. Extending from the tank 39 is a pipe 41 which has mounted therein and in communication therewith a blast valve mechanism indicated generally at 43. The blast valve mechanism has a housing which communicates through a short section of pipe 45 with the passage through the interior of the insulator 13. The passage through the insulator 13 communicates through a pipe 47 and through the hollow insulator 21 with the chamber of the circuit interrupting element 23. Thus, a blast of air under pressure from the tank 39 is conducted to the arc extinguisher 60 by way of the pipe 41, blast valve 43, insulator 13, pipe 47, and insulator 21. The blast valve mechanism 43 is of the same construction as that disclosed in the aforementioned copending application of L. R. Ludwig et al., Serial No. 431,394, filed February 18, 1942, and, consequently, only a brief description thereof is given here since reference to the aforementioned application may be had for details of construction. The blast valve mechanism includes a valve 49 which is biased to closed position by a spring and which is caused to be opened by air pressure upon energization of a solenoid 51.

The movable contact member 31 is operated to open and to closed circuit position by a compressed air operating means comprising an operating cylinder 53 having a double-acting operating piston, indicated generally at 55, therein which is coupled to the contact member 31. The operating cylinder 53 is mounted within the casing 19 and has a lower cylinder head 57 secured thereto by bolts 59, the cylinder head being, in turn, secured to the casing 19 by extensions 61 which are bolted to the bottom wall of the casing. The lower portion of the movable contact member 31 slidably extends through the offset portion of the pipe 47 and through an opening provided therefor in the upper head 64 of the cylinder, and the lower end of the contact member is coupled to the operating piston 55.

The operating cylinder 53 has a projection 63 formed integral therewith adjacent the upper end, and this projection has an inlet air passage 65 leading to the upper end of the interior of the operating cylinder. The projection 63 also has a port (not shown) communicating with the passage 65, and this port is connected by a pipe 67 (Fig. 1) to the passage of the hollow insulator 17. The passage of the hollow insulator 17 is, in turn, connected by a pipe 69 (Fig. 3) to an opening valve mechanism 71 for controlling the flow of compressor air to effect an opening operation of the circuit breaker.

The lower end of the operating cylinder 53 is also provided with an integral projection 73 having an air passage 75 therein communicating with the lower end of the operating cylinder, and this projection has a port (not shown) which communicates with a pipe 77 (Fig. 1). The other

end of the pipe 77 communicates with the passage through the supporting insulator 15 to the lower end of which is connected a pipe 79 leading to a closing valve mechanism, indicated generally at 81.

Compressed air for operating the piston 55 to effect opening and closing of the circuit interrupter is derived from the air storage tank 39. For this purpose, the pipe 41 is provided with two branch pipes 83 and 85 (Fig. 3). The pipe 83 is connected to the opening valve mechanism 71, whereas the branch pipe 85 is connected to the closing valve mechanism 81. Compressed air from the opening valve 71 is conducted through the pipe 69 and passage of insulator 17 and pipe 67 to the upper end of the operating cylinder. Closing valve mechanism 81 controls the flow of compressed air through the pipe 79, passage through insulator 15 and pipe 77 to the lower end of the operating cylinder 53 to effect closing operation of the circuit interrupter.

In order to obtain high speed opening and high speed reclosing operation of the breaker, it is necessary to dump the air in the cylinder ahead of the direction of movement of the operating piston to atmosphere so as to prevent air ahead of the piston from retarding the movement thereof. Two dump valves 87 and 89 are provided for this purpose. The dump valve 89 is mounted in a projection 91 formed integral with the cylinder adjacent its upper end. This projection has a passage 93 leading to the upper portion of the operating cylinder and also has an atmosphere exhaust port 95 which is normally closed by the valve 89. The valve 89 has a rod 97 connected thereto, the lower end of which engages a dump valve operating piston 99 that is movable in a cylinder provided in the projection 73. The dump valve 89 is biased closed by a spring 101 and is adapted to be operated to open position by the valve piston 99 immediately upon the flow of compressed air to the lower side of the breaker operating piston 55. Opening of the valve 89 opens the upper end of the operating cylinder 53 to atmosphere through the port 95, so that air above the breaker operating piston 55 will be at a low pressure, and hence will not retard closing movement of the piston.

The other dump valve 87 is mounted in a projection 103 formed integral with the cylinder 53 adjacent the lower end thereof. The projection 103 has a passage 105 therein which communicates with the lower portion of the breaker operating cylinder 53, and also has an exhaust port 106 leading to atmosphere. The dump valve 87 has an operating rod 107 connected thereto, the upper end of which engages the valve operating piston 109 movably mounted in a cylinder of the projection 63. The dump valve 87 is biased closed by a spring 111 and is adapted to be opened by the valve piston 109 immediately upon the flow of compressed air to the upper end of the breaker operating cylinder 53. Opening of the dump valve 87 connects the lower portion of the breaker operating cylinder 53 to atmosphere through the exhaust port 106, thereby causing air below the breaker operating piston 55 to be at a low pressure so that it will not retard the opening movement of the operating piston.

The opening valve mechanism 71 and the closing valve mechanism 81 are of the same construction as disclosed in the aforementioned copending application of L. R. Ludwig et al., Serial No. 431,394, and only a brief description thereof will

be given in this application as the details of construction of the valve mechanisms are not necessary for a complete understanding of the present invention. Referring to Fig. 3, the opening valve mechanism 71 has a valve 113 which is biased closed and which is caused to be opened by a valve piston operated by air pressure in the pipe 83 upon energization of a solenoid 115. Similarly, the closing valve mechanism 81 has a valve 117 which is biased closed and which is caused to be opened by a valve piston operated by compressed air from the pipe 85 upon energization of a solenoid 119. The valve mechanisms 71 and 81 are pneumatically interlocked by means of a pipe 121, as disclosed in the aforementioned copending application of L. R. Ludwig et al., Serial No. 431,394, so that an opening impulse will always take precedence over a closing impulse.

The control circuits for controlling the solenoid 51 of the blast valve mechanism 49 and the solenoids 115 and 119 of the opening and closing valves may be substantially the same as disclosed in the aforementioned copending application of L. R. Ludwig et al., Serial No. 431,394, and are not shown in this application as the details thereof are unnecessary for an understanding of the present invention. It is believed sufficient to state that the solenoid 51 of the blast valve mechanism and the solenoid 115 of the opening valve mechanism are adapted to be simultaneously energized in response to operation of an opening relay. The opening relay is energized in response to operation of an overload current responsive relay or by a manual opening control switch. As soon as the opening operation of the interrupter is completed, the opening relay is de-energized so that the valves return to closed position. The solenoid 119 of the closing valve mechanism 81 is caused to be energized by the operation of a closing relay controlled either by a manual closing control switch or by a suitable reclosing relay. As soon as the closing operation is completed, the closed relay is deenergized, whereupon the closing valve 81 is returned to closed position.

In accordance with the present invention, the mechanism is provided with an improved mechanical shock-absorbing system comprising a series of elements, masses and resilient means arranged to absorb the kinetic energy of the moving parts without developing high impact forces. Referring to Fig. 2, the shock-absorbing system includes a pair of annular metal bumpers 125 and 127 which are resiliently supported in the opposite ends of the operating cylinder 53 in positions to be engaged by the operating piston as it approaches each end of its stroke. The bumpers 125 and 127 are mounted for limited vertical movement in the slightly enlarged bore portions which are provided in each end of the operating cylinder 53, and the outer diameter of the bumpers 125 and 127 is only slightly less than that of the enlarged bore portions.

Resilient means comprising a plurality of annular rings 129 of resilient or elastic material are disposed in back of each of the bumpers 125 and 127 for the purpose of absorbing some of the energy. Downward movement of the upper bumper 127 is limited by the shoulder formed by the upper enlarged bore portion adjacent the upper end of the cylinder, and the resilient rings 129 for this bumper are disposed between the bumper and the head 64 of the cylinder. Upward movement of the lower bumper 125 is limited by the shoulder formed by the lower enlarged

bore portion adjacent the lower end of the cylinder, and the resilient rings 129 for this lower bumper 125 bear against the underside of the bumper, a metal ring 131 being provided beneath the lowermost ring 129. The outer diameter of the resilient rings 129 and the metal ring 131 is only slightly less than the diameter of the enlarged bore portion so that these rings have a relatively close fit in the bore. The lower metal bumper 125 and its resilient rings 129 are supported on the enlarged head 133 of a movable inertia mass 135 which is mounted for limited vertical movement in a bore of the lower cylinder head 57. This inertia mass is, in turn, supported by a relatively heavy helical compression spring 137 disposed in the bore of the lower cylinder head 57. The upper end of the spring 137 bears against the enlarged head of the inertia mass and the lower end of the spring bears against a closure cap 139 which is secured to the lower end of the cylinder head 57 by a plurality of screws 141. The spring 137 biases the inertia mass and the bumper assembly to its upper limiting position, as shown in Fig. 2. In this position the lower end of the inertia mass is disposed in slightly spaced relation to a cylindrical bumper stop 143 which is composed of resilient material, such as rubber. The bumper stop 143 is mounted within a well provided therefor in the closure cap 139.

The breaker operating piston 55 has a resilient shock-absorbing means comprising a spring built therein which acts to absorb some of the kinetic energy of the moving parts at each end of the stroke of the piston. The operating piston 55 comprises an outer metal shell 145 through which the lower portion of the contact member 31 extends. The upper end of the piston shell 145 has an inwardly extending integral flange portion 147, and a ring or bushing 149 is threaded into the lower end of the shell 145. A pair of flanged metal rings 151 and 153 are movably mounted within the shell 145 adjacent the opposite ends thereof, the outer necks of these rings 45 being slidably received in the flange 147 and bushing 149, respectively. A helical shock-absorbing compression spring 155 is mounted within the shell 145 and is disposed between the flange portions of the movable rings 151 and 153. The contact member 31 has a reduced portion 151 which extends downwardly through the rings 151 and 153, and the shoulder provided by this reduced portion of the contact member bears against and abuts the upper end of the movable ring 151. A lock nut 159 is threaded on the lower end of the reduced portion of the contact member 31, and this nut bears against and abuts the lower edge of the lower movable ring 153, as shown in Fig. 2. It will thus be seen that the piston shell 145 is resiliently coupled to the contact member 31. The upper end of the movable inertia mass 135 is provided with a recess 161 to accommodate the projecting lower threaded end of the movable contact member 31.

The resilient rings 129 which are associated with the metal bumpers 125 and 127 are composed of a resilient or elastic material which suffers deformation with very little volumetric compression upon impact or compression of the rings, one suitable material being rubber, for example. Upon impact, the resilient rings 129 are deformed and the sides thereof expanded and pressed tightly against the bore of the cylinder so as to exert a frictional braking action against the bore of the cylinder as they are moved along

with the piston. This braking action decelerates the piston 55 and moving parts, and upon release of the driving force, the braking action is automatically removed, and the rings returned to their original shape.

The operation of the circuit interrupter is briefly as follows: Assuming the circuit breaker to be in the open position as illustrated in Figs. 1 and 2, closing operation of the circuit breaker is caused to take place upon energization of the closing valve solenoid 119. Opening of the closing valve 81 causes the flow of compressed air from the storage tank 39 through the branch pipe 85, closing valve 81, hollow insulator 15, and pipe 77 to the lower side of the breaker operating piston 55. The flow of compressed air immediately causes opening of the dump valve 89 and effects movement of the operating piston 55 upwardly to its upper end position, thereby closing the circuit breaker.

An opening operation of the circuit breaker is produced upon energization of the opening valve solenoid 115. Opening of the valve 71 causes the flow of compressed air from the storage tank 39 through the branch pipe 83, opening valve 71, hollow insulator 17, and pipe 67 to the upper side of the breaker operating piston 55. This flow of compressed air immediately causes opening of the dump valve 87, thereby opening the lower end of the cylinder to atmosphere, and the compressed air acting on the top of the operating piston 55 moves the same downwardly to its lowermost or open position, thereby effecting opening of the circuit breaker. Since the blast valve controlling electromagnet 51 is energized simultaneously with the opening valve solenoid 115, a blast of compressed air is directed to the circuit interrupting element 23 to quickly extinguish the arc drawn by the movable contact member 31 during the initial portion of the opening operation.

During the latter portion of the downward or opening movement of the operating piston 55, the shell 145 thereof strikes the lower metal bumper 125. The impact compresses the shock-absorbing spring 155 and also compresses and deforms the resilient rings 129, thereby absorbing some of the kinetic energy. The metal bumper 125, rings 129, and the relatively heavy inertia mass 135 are thereby accelerated and moved downwardly by the piston to compress the relatively heavy spring 137, thereby absorbing additional amounts of kinetic energy. The compression of the resilient rings 129 causes the sides thereof to be expanded and pressed tightly against the enlarged bore portion of the cylinder, thereby exerting a considerable frictional braking action as these rings are moved along with the piston. This action absorbs some more of the kinetic energy of the moving parts. The lower end of the inertia mass finally strikes the resilient bumper stop 143, compressing the same and bringing the parts to a stop as the remaining portion of the energy is absorbed. After the motion of the piston has been brought to a stop, the spring 137 and the resilient rings 129 expand and return the parts to the normal position, as shown in Fig. 2.

During the final portion of the closing operation, the kinetic energy is absorbed by the piston 55 striking the upper bumper plate 127 and compressing the upper resilient rings 129 and the shock-absorbing spring 155 of the piston itself. The closing speed of the piston is not as high as the opening speed, and the tulip type

stationary contacts 30 absorb some of the kinetic energy during the final portion of the closing operation.

While the invention has been disclosed in accordance with the provisions of the patent statutes, it is to be understood that various changes in the structural details and arrangement of parts may be made without departing from some of the essential features of the invention. It is, therefore, desired that the language of the appended claims be given the broadest reasonable interpretation permissible in the light of the prior art.

We claim as our invention:

15. In a circuit breaker, movable contact means, high speed operating means therefor including a movable member connected to said contact means, shock-absorbing means comprising a metal bumper movably mounted in a guide, resilient means of deformable material in back of said bumper, said resilient means being deformed by impact and thereby pressed tightly against said guide to exert a braking action for decelerating said movable member, a movable inertia mass supporting said resilient means and bumper, and spring means supporting said inertia mass.
20. In a high speed circuit breaker operating mechanism, a cylinder, a fluid operated piston in said cylinder for actuating the breaker, shock-absorbing means comprising a metal bumper slidably supported in one end of said cylinder, resilient means of deformable material in back of said bumper, said resilient means being deformed by impact and the sides thereof thereby pressed tightly against the wall of said cylinder to exert a braking action for decelerating said piston, a movable inertia mass supporting said resilient means and bumper and spring means supporting said inertia mass.
25. In a circuit breaker, movable contact means, high speed operating means therefor including a member connected to said contact means, shock-absorbing means comprising a resilient shock absorber carried by said member and effective to absorb some of the kinetic energy at each end of the stroke, a metal bumper movably supported in a guide and disposed to be engaged by said resilient shock absorber, a movable inertia mass supporting said metal bumper, and resilient means supporting said inertia mass.
30. In a circuit breaker, movable contact means, high speed operating means therefor including a movable member connected to said contact means, shock-absorbing means comprising a resilient shock absorber carried by said movable member and effective at each end of the stroke to absorb some of the kinetic energy, a metal bumper movably supported in a guide and disposed to be engaged by said resilient shock absorber, resilient means of deformable material in back of said bumper, said resilient deformable means being deformed by impact and its sides thereby pressed tightly against said guide to exert a braking action for decelerating said movable member, a movable inertia mass supporting said resilient deformable means and said bumper, and spring means supporting said inertia mass.
35. In a circuit breaker, movable contact means, high speed operating means therefor including a member connected to said contact means, shock-absorbing means comprising a resilient shock absorber carried by said member and effective to absorb some of the kinetic energy at each end of the stroke, a metal bumper movably supported in a guide and disposed to be engaged by said resilient shock absorber, a movable inertia mass supporting said metal bumper, and resilient means supporting said inertia mass.
40. In a circuit breaker, movable contact means, high speed operating means therefor including a member connected to said contact means, shock-absorbing means comprising a resilient shock absorber carried by said member and effective to absorb some of the kinetic energy at each end of the stroke, a metal bumper movably supported in a guide and disposed to be engaged by said resilient shock absorber, a movable inertia mass supporting said metal bumper, and resilient means supporting said inertia mass.
45. In a circuit breaker, movable contact means, high speed operating means therefor including a member connected to said contact means, shock-absorbing means comprising a resilient shock absorber carried by said member and effective to absorb some of the kinetic energy at each end of the stroke, a metal bumper movably supported in a guide and disposed to be engaged by said resilient shock absorber, a movable inertia mass supporting said metal bumper, and resilient means supporting said inertia mass.
50. In a circuit breaker, movable contact means, high speed operating means therefor including a member connected to said contact means, shock-absorbing means comprising a resilient shock absorber carried by said member and effective to absorb some of the kinetic energy at each end of the stroke, a metal bumper movably supported in a guide and disposed to be engaged by said resilient shock absorber, a movable inertia mass supporting said metal bumper, and resilient means supporting said inertia mass.
55. In a circuit breaker, movable contact means, high speed operating means therefor including a member connected to said contact means, shock-absorbing means comprising a resilient shock absorber carried by said member and effective to absorb some of the kinetic energy at each end of the stroke, a metal bumper movably supported in a guide and disposed to be engaged by said resilient shock absorber, resilient means of deformable material in back of said bumper, said resilient deformable means being deformed by impact and its sides thereby pressed tightly against said guide to exert a braking action for decelerating said movable member, a movable inertia mass supporting said resilient deformable means and said bumper, and spring means supporting said inertia mass.
60. In a circuit breaker having relatively movable contacts, high speed operating means therefor comprising a cylinder, a contact actuating rod slidably extending into said cylinder through one end, a fluid pressure operated piston in said cylinder coupled to said rod for actuating the breaker, and means including a single spring
65. In a circuit breaker having relatively movable contacts, high speed operating means therefor comprising a cylinder, a contact actuating rod slidably extending into said cylinder through one end, a fluid pressure operated piston in said cylinder coupled to said rod for actuating the breaker, and means including a single spring
70. In a circuit breaker having relatively movable contacts, high speed operating means therefor comprising a cylinder, a contact actuating rod slidably extending into said cylinder through one end, a fluid pressure operated piston in said cylinder coupled to said rod for actuating the breaker, and means including a single spring
75. In a circuit breaker having relatively movable contacts, high speed operating means therefor comprising a cylinder, a contact actuating rod slidably extending into said cylinder through one end, a fluid pressure operated piston in said cylinder coupled to said rod for actuating the breaker, and means including a single spring

means mounted on said piston and absorbing energy at both ends of the travel of said piston.

6. In a circuit breaker having relatively movable contacts, high speed operating means therefor comprising a cylinder, a breaker actuating rod slidably extending into said cylinder through one end thereof, a fluid pressure operated piston in said cylinder coupled to said rod for operating the breaker, a shock-absorbing bumper adjacent each end of said cylinder in a position to be engaged by said piston, and one resilient means mounted on said piston and absorbing energy at both ends of the travel of said piston.

7. In a high speed circuit breaker operating mechanism, a cylinder, a breaker actuating rod slidably extending into said cylinder through one end, a fluid pressure operated piston in said cylinder coupled to said rod for operating the breaker, shock-absorbing means including resilient means adjacent each end of said cylinder and a spring means carried by said piston and absorbing energy at both ends of the travel of said piston.

8. In a high speed circuit interrupter operating mechanism, a cylinder, an interrupter actuating rod slidably extending into said cylinder through one end thereof, a fluid pressure operated piston in said cylinder coupled to said rod for operating the interrupter, a movable inertia mass mounted in said cylinder adjacent one end, means for resiliently opposing movement of said mass, and spring means carried by said piston and through which the energy of said actuating rod is transmitted to said inertia mass for absorbing energy at one end of the travel of said piston.

9. In a high speed circuit interrupter operating mechanism, a cylinder, an interrupter actuating rod slidably extending into said cylinder through one end thereof, a fluid pressure operated piston in said cylinder coupled to said rod for operating the interrupter, shock-absorbing means comprising a metal bumper movably mounted adjacent each end of said cylinder, resilient means of deformable material in back of each bumper, and spring means through which said actuating rod is coupled to said piston for absorbing energy at both ends of the travel of said piston upon engagement with said bumpers.

10. A high speed circuit breaker operating mechanism comprising a cylinder, a breaker actuating rod slidably extending into said cylinder through one end, a fluid operated piston in said cylinder coupled to said rod for operating the breaker, said piston comprising a shell through which said breaker actuating rod extends, a pair of rings movably mounted in said shell, and a spring disposed in said shell between said rings, said rod having portions on opposite sides of said piston abutting said rings.

11. A high speed circuit breaker operating mechanism comprising a cylinder, a contact actuating rod slidably extending into said cylinder through one end thereof, a fluid operated piston in said cylinder coupled to said rod for operating the breaker, said piston comprising a

shell through which said rod extends, a pair of rings movably mounted in said shell one adjacent each end, said shell having end portions to limit outward movement of said rings, a compression spring disposed in said shell between said rings, said rod having a shoulder portion at one end of said piston for abutting one of said rings and having removable means on the other side of the piston for abutting the other ring, and resiliently mounted bumper means adjacent at least one end of said cylinder adapted to be engaged by one end portion of said piston.

12. In a circuit breaker having relatively movable contacts, high speed operating means therefor comprising a cylinder, a contact actuating rod slidably extending into said cylinder through one end, a fluid pressure operated piston in said cylinder, resilient means by which said piston is coupled to said rod for actuating the breaker, and said resilient means being mounted in said piston between the opposite end surfaces of the piston and absorbing kinetic energy at both ends of the travel stroke of said piston.

13. In a high speed circuit breaker operating mechanism, a cylinder, a fluid operated piston in the cylinder for actuating the breaker, and shock-absorbing means including resilient means disposed at least at one end of the cylinder and a biased inertia member backing up said resilient means to help decelerate the piston when it engages the resilient means at the end of its stroke.

14. In a high speed circuit breaker, movable contact means, a cylinder, a fluid operated piston reciprocal in the cylinder and mechanically connected through resilient means to the contact means to cause the operation thereof, and a heavy movable inertia means disposed at one end of the cylinder and biased against movement under impact from the piston to assist in decelerating the piston.

15. In a circuit breaker having relatively movable contacts, high speed operating means therefor comprising a cylinder, a contact actuating rod slidably extending into said cylinder through one end, a fluid pressure operated piston in said cylinder coupled to said rod for actuating the breaker, a weight member to which the energy of said piston is transmitted by impact, a spring for absorbing energy from said weight member and means of resilient deformable material for finally stopping the travel of the weight member and the piston.

16. In a circuit breaker having relatively movable contacts, operating means therefor comprising a cylinder, a contact actuating rod slidably extending into said cylinder, a fluid pressure operated piston in said cylinder, stop means at each end of said cylinder engageable by said piston, and resilient means coupling said piston to said contact actuating rod and reducing the shock when the piston engages each of the stop means.
